UNITED STATES PATENT OFFICE.

GEORGE W. MORSTATT, OF NEW YORK, N. Y.

MACHINE FOR INSERTING PINS IN BLIND-SLATS.

SPECIFICATION forming part of Letters Patent No. 314,464, dated March 24, 1855.

Application filed August 1, 1884. (No model.)

To all whom it may concern:

Be it known that I, GEORGE W. MORSTATT, of the city and county of New York, in the State of New York, have invented a certain new and useful Improvement in Machines for Inserting Pins in Blind Slats, of which the following is a specification.

The object of my invention is to provide a machine whereby metal pins previously cut to the desired length may be accurately and quickly inserted and forced into holes previously bored in the ends of blind-slats, the pins serving as substitutes for the ordinary tenons on the ends of the slats.

15 My improved machine may be employed to insert a pin in each end of the slat, and in addition thereto, if desired, a smaller pin in one end of the slat near the edge, the latter serving for the attachment of an adjusting-rod, where-
20 by the slats may be adjusted as shown and de-
scribed in my Letters Patent No. 291,924, dated January 15, 1884.

My invention will be fully hereinafter described; and it consists in novel combinations 25 of parts set forth in the claims.

In the accompanying drawings, Figure 1 is a vertical longitudinal section of a machine embodying my invention. Fig. 2 is a plan of the machine, the two hoppers which supply pins thereto being removed. Fig. 3 represents a slat with the pins inserted; and Figs. 4, 5, and 6 are respectively transverse sections on the dotted lines $x-x$, $y-y$, $z-z$, Figs. 1 and 2.

Similar letters of reference designate corresponding parts in all the figures.

A designates a bed-plate or stationary frame composed of metal and supported on legs or standards A'.

The bed-plate or frame A is constructed with a fixed head or stock piece, A*, at one end, and has guides or ways *a* in opposite sides, forming a slideway, wherein is fitted an adjustable head or stock, B, capable of sliding toward and from the fixed head or stock A*.

ward and from the fixed head or stock A. 45 This adjustment of the head or stock B adapts the machine for receiving longer or shorter blind-slats C to be operated on, as hereinafter described; but if the machine is intended to operate on slats of one length only the head 50 B may be non-adjustable.

From the adjustable head Bascrew-threaded

rod, B', extends rearward and through a bearing, b, in the rear end of the frame A, and nuts c c are applied to the said rod on both sides of the bearing. By turning these nuts on the rod the movement of the rod through the bearing is provided for, and after the head B is brought to the desired distance from the fixed head A* the nuts c are tightened against the bearing, and the head B is thus held securely against displacement. 6.

Between the fixed and adjustable heads A* B there are two cross-pieces, D D', which are notched at *, to receive and properly center the slat C when placed upon them. The piece 65 D is fixed, but the piece D' is adjustable in the ways a, and when the head B is moved it is also moved correspondingly, the two pieces D D' supporting the slat C near opposite ends.

The slat shown in Fig. 3 has at opposite ends pins d , which form the slat-tenons, and at one end is a smaller pin, d' , with which the slat-adjusting rod is to be connected. 70

On the head B is arranged a hopper, E, which is to contain pins d , and on the head A* is a divided hopper or two hoppers, E' E*, which are to contain, respectively, the pins d and d' . The throat or outlet e of the hopper E is controlled by a feeding wheel or roller, f , which is turned step by step, and fluted or grooved on its periphery to receive the pins, whereby it is made to deliver the pins one by one from the hopper E. The arrangement of the wheel or roll f and its relation to the delivery-throat e of the hopper E will be understood from Fig. 4. The outlet-throats $e' e^*$ of the hoppers E' E* are controlled by similar wheels or rolls, $f' f^*$, which are also fluted or grooved longitudinally, and have a step-by-step rotary motion. The construction of the rolls $f' f^*$ and their relation to the outlet-throats of the two hoppers E' E* will be understood from Fig. 5.

The shafts of the two rolls $f' f^*$ are geared together by pinions $f^2 f^3$, as shown in Figs. 2 95 and 6, and are operated as hereinafter described, and the shaft f^4 of the roll f' is prolonged and extends through the roll f , controlling the outlet of the hopper E. This shaft is grooved at 2, and the roll f is locked to it 100 by a spline or feather. Whenever the head B is adjusted toward or from the head A*, the

roll f slides along the shaft f^4 and receives rotary motion from the shaft in whatever position thereon it may be.

In the head A^* is a longitudinal slideway, 5 g , in the bottom of which are grooves or seats $g' g^*$ directly below the outlet-throats $e' e^*$ of the hoppers $E' E^*$, and into which the pins drop from said hoppers.

In the slideway g is a slide or plunger, h , 10 which is reciprocated by a connecting-rod, F , and a crank, F' , upon a crank-shaft, F^2 , which is journaled in a bearing, A^2 , projecting from the frame or bed A .

Upon the shaft F^2 is a pulley, F^3 , to 15 receive a driving-belt. This pulley is loose on the shaft, and is locked thereto by a sliding clutch-piece, F^4 , which is connected with the shaft by a spline or feather, 3, and can therefore move longitudinally on the shaft. This clutch-piece 20 F^4 may be operated by a treadle and suitable connections in any well-known manner; but as such means of moving a clutch are well-known in various kinds of machinery and are not claimed by me I have not shown them.

25 I have here shown the connecting-rod F as composed of two pieces connected by a screw-thread and jam-nut, $i' i$, and it can therefore be varied in length, so as to definitely fix the range of movement of the plunger h .

30 On the under side of the plunger h are attached ribs or tongues $h' h^*$, which fit and slide in the pin-seats $g' g^*$ in the slideway g and eject the pins from these seats as the plunger moves forward. These tongues $h' h^*$ are preferably adjustable, and, as shown in Figs. 1 and 6, they are fitted in dovetailed grooves in the under side of the plunger or slide, and may be adjusted each by means of a screw, h^2 , fitted in a lug or ear, 4, on the under side of 40 the plunger. At the front end the tongues or ribs $h' h^*$ have slight depressions, as shown at 5, Fig. 1, and as the pins $d' d$ are pointed or slightly conical, as shown in Fig. 3, the ends of the pins are prevented from slipping laterally off the ribs or tongues as they are 45 forced forward by said ribs or tongues.

In the head or stock B is a slideway, j , closed by a cap piece or plate, B^* , and in which is fitted a slide or sliding pin-support, G , which 50 has in its top a groove, k , which receives the pin as it is dropped from the outlet-throat e of the hopper E . This piece G is supported at the rear end by springs l , one of which is shown in Fig. 1, and which are shown dotted in Figs. 2 and 4. The springs press the piece 55 G outward into the position shown in Fig. 1; but its further outward movement is limited by a screw or pin, l' , which is inserted through the cap piece or plate B^* and into a slot in the 60 piece G . Being supported by springs at its rear end, the piece G will yield to pressure at its front end, and may be forced back by pressure against the front end.

65 On the under side of the cap piece or plate B^* , and projecting downward into the groove or pin-seat k , is a tongue or rib, k' , which is formed with a slight cavity or depression at

its front end, so as to prevent a pin from slipping off it, and when the slide G is pushed inward the pin in the pin-seat k will be held by 70 the tongue or rib k' , and the slat C will be forced onto the pin.

75 Adjacent to the wheel or pinion f^3 on the feed-roll f^* is a stud or fixed pin, m , on which are a ratchet-wheel, m' , and a pinion, m^2 , which rotate together, and the latter of which, m^2 , 75 gears into the pinion f^3 .

On the stud or pin m is loosely fulcrumed a bell-crank or elbow lever, m^3 , as best shown in Fig. 6, and which carries a pawl, m^4 , held by 80 a spring, m^5 , in engagement with the ratchet-wheel m' . The lever m^3 is connected by a link or rod, n , with one end of the lever H , which is fulcrumed at n' , and which is acted upon by a spring, n^2 , to raise that end of the lever H 85 which is connected with the pawl-carrying lever m^3 , and to so move the pawl m^4 back on the wheel m' to take a new hold thereon.

The front end of the lever H bears on a cylindric hub or roll, I , on the shaft F^2 , and the 90 said hub or roll has a protection or cam, o , which acts upon that end of the lever H , and thereby moves it against the action of the spring n^2 , and causes the pawl m^4 to turn the ratchet-wheel m' , and through the gearing 95 above described to also turn the feed-rolls $f' f^*$ a sufficient distance to drop the pins $d' d$ d into their seats $g' k g^*$, which are formed in the head A^* and in the slide G . When the plunger or slide h is drawn back, the crank-shaft is stopped by the clutch, and the slat C is placed in proper position on the notched supports $D D'$, the notches or slat-seats * being in such position that the slat is supported with its pin-holes in line with the grooves or 100 seats $g' k g^*$. The crank-shaft F^2 is now started by the throwing of the clutch into gear, and by the first movement the cam o acts on the lever H to turn the feed-rolls and deposit pins in the pin-seats $g' k g^*$. This is done 110 while the crank is passing the center, and hence the pins are deposited before the plunger h commences its forward movement. As the plunger or slide h moves forward, its ribs or tongues $h' h^*$ strike the ends of the pins 115 in the pin-seats $g' g^*$, and so thrust the pins forward and enter them into the holes in the slats. By the continued movement of the plunger the slat itself moves forward, the slide G yielding to it or moving with it; but the 120 pin in the pin-seat k is prevented from moving by the fixed tongue or rib k' , and the slat is thereby forced onto the pin. During the remainder of the forward movement of the plunger or slide h the pins at both ends of 125 the slats are held by the ribs or tongues $h' h^*$ at the one end of the slat and the rib or tongue k' at the other end thereof, and thereby the pins are all forced tightly into the slat. At the termination of its return movement the 130 shaft F^2 is stopped, and the slat with its pins is removed, and a second slat is placed on the slat seats or bearings $D D'$, whereupon the clutch is again thrown in and the operation

repeated. As soon as the pressure is removed from the slide G the latter returns to its former position, where it is shown in Fig. 1.

By this machine the slats have their tenon-pins, which are commonly made of brass wire, forced into their previously-bored holes tightly and accurately.

The slide G forms a yielding abutment for supporting the slat at one end.

10. What I claim as my invention, and desire to secure by Letters Patent, is—

1. The combination, with a bed-plate or frame and a head or stock piece, A*, provided with a slideway having in its bottom a groove or pin-seat, of a hopper for pins, and a pin-feeding roll or device controlling the outlet therefrom, a reciprocating plunger or slide working in said slideway, and having on its under side a tongue or rib fitting said groove or pin-seat and serving to force a pin from said groove or seat into one end of a blind-slat, an abutment for the other end of the slat, and a slat-support between the head A* and said abutment, substantially as herein described.

2. The combination, with a bed-plate or frame and a head or stock piece, A*, provided with a slideway having in its bottom grooves or pin-seats, of hoppers for pins and feed-rolls geared together and controlling the outlets of said hoppers, a reciprocating plunger working in said slideway, and having on its under side tongues or ribs fitting said grooves or pin-seats and serving to force pins therefrom into one end of a blind-slat, an abutment for the other end of the slat, and a slat-support between said head and abutment, substantially as herein described.

3. The combination, with a bed-plate and a head, A*, formed with a slideway, g, in the bottom of which is a pin-seat or groove, g', of the pin-hopper E' and its roll f', having a step-by-step rotation, the reciprocating plunger or slide h, provided with a rib or tongue, h', fitting the pin-seat or groove g' and adjustable lengthwise relatively to the plunger or slide, an abutment for supporting the slat against free movement lengthwise, and a slat-support

between said head and abutment, substantially as herein described.

4. The combination, with a bed-plate and a head, A*, constructed with a grooved slideway, g g' g*, of the pin-hoppers E' E* and their feed-rolls f' f*, geared together, the ribbed or tongued plunger h h' h*, the ratchet-wheel m', 55 geared with said rolls, the pawl-carrying lever m* and its pawl, the spring-actuated lever H, and the crank-shaft and its cam I o, all substantially as herein described.

5. The combination, with a bed-plate and a head or stock piece constructed with a slideway, of a yielding abutment having a groove or pin-seat in its upper surface, a pin-hopper and pin-feeding device controlling its outlet, a tongue or rib fitting said groove or pin-seat 65 and forming a fixed abutment for the pins, a reciprocating plunger for forcing the slats against said yielding abutment and upon the pins, and a slat-support, substantially as herein described.

6. The combination, with a bed-plate and a head or stock piece, B, constructed with a slideway, j, the spring-supported slide G, having a groove or pin-seat, k, in its upper surface, the tongue or rib k', fitting said groove or pin-seat, 75 the hopper and feed-roll E f, the slat-support D D', and a reciprocating plunger for forcing the slats endwise against the slide G and upon their pins, substantially as herein described.

7. The combination, with a bed-plate and two heads or stocks, each constructed with a slideway, and one of said slideways having in its bottom a groove or grooves, of a reciprocating plunger working in the last-named slideway and tongued or ribbed to fit the groove 85 or grooves thereof, a slide fitting the other slideway and grooved to form a pin-seat, pin-hoppers and feed devices controlling the outlets thereof, and a slat-support between the heads or stocks, all substantially as herein described.

G. W. MORSTATT.
